SOUND RECORDING SYSTEM

William Maurice Patterson, Fairland, Ind., assignee to Westinghouse Electric & Manufacturing Company, a corporation of Pennsylvania

Application June 11, 1931, Serial No. 543,507

12 Claims. (Cl. 179—100.3)

My invention relates to acousto-cinematographic apparatus and has particular relation to apparatus of a type wherein a directional effect is introduced into the sound reproduced with a motion picture that corresponds to the elements of the picture that are shown to produce the sound.

In acousto-cinematographic apparatus constructed and operated according to the teachings of the prior art, of which I am aware, the sound is reproduced from a plurality of loudspeakers disposed adjacent to the screen in accordance with some prearranged scheme. The loudspeakers are, at any instant, all energized to the same extent and, in consequence thereof, the sound emanating from the region of the screen has the property of homogeneity in direction. The points on the screen from which the sound should emanate vary as persons depicted appear to move across the screen. The effect produced by such an arrangement is rather strange and, at times, even ludicrous. Moreover, when a number of persons are portrayed as speaking simultaneously, the result is rather confusing to the audience, since the sounds that are shown as coming from the characters cannot be distinguished.

It is, accordingly, an object of my invention to provide acousto-cinematographic apparatus wherein the sound reproduced shall have a directional characteristic.

Another object of my invention is to provide acousto-cinematographic apparatus wherein the sound produced shall emanate from a region of a screen corresponding to the position of the picture element by which the sound is apparently produced.

A further object of my invention is to provide acousto-cinematographic apparatus of a type wherein the elements of a picture from which a plurality of sounds are apparently emanating shall be distinguishable by reason of the direction in which the sound is actually being projected.

A specific object of my invention is to provide a recording device of a type wherein a record shall be impressed on a permanent medium in such manner that the relative disposition of the elements from which the original sound emanated shall be distinguishable.

A further specific object of my invention is to provide photo-acoustic sound-recording apparatus of a type wherein the record to be reproduced shall have the property of reproducing the direction in which a sound that was originally recorded was projected.

A still further specific object of my invention

is to provide cine-acoustic recording apparatus of a type wherein the recording elements shall respond to the relative disposition of the objects from which the sound to be recorded is emanating.

Still a further specific object of my invention is to provide reproducing apparatus of a type wherein the sound emanating from a given region shall have a predetermined heterogeneity in direction.

Another specific object of my invention is to provide reproducing apparatus of a type wherein the sound emanating from a given region shall have a heterogeneity in direction that shall be so variable with respect to time as to correspond to the picture projected.

Still another specific object of my invention is to provide reproducing apparatus to be utilized in an acousto-cinematographic system of a type wherein the sound reproduced shall emanate from regions predetermined by the disposition of the elements in the recording setting.

An incidental object of my invention is to provide a sound record particularly adapted to be utilized in directional acousto-cinematographic apparatus.

A further incidental object of my invention is to provide a sound record of a type having a property whereby the directional effects of sound shall be capable of being recorded.

Another incidental object of my invention is to provide a photo-sensitive device particularly adapted to be utilized in directional cinema-acoustic reproduction.

Still another incidental object of my invention is to provide a photo-sensitive device to respond to localized excitation in a predetermined manner.

A still further object of my invention is to provide a photo-sensitive device that shall be capable of responding to localized excitation in a manner that shall lend itself to the spacial rearrangement of elements energized by the device.

More concisely stated, an object of my invention is to provide reproducing and recording apparatus of a type that shall cooperate in producing acousto-cinematographic entertainment wherein the elements of a picture from which a sound appears to emanate shall correspond, in a natural and expected manner, to the original source of such sound.

According to my invention, a plurality of devices for translating acoustic disturbances in the air into electrical energy, such as microphones, are disposed in a predetermined manner in the vicinity of a setting to be photographed and

recorded. The sound impressed on the microphones is amplified and the outputs of the amplifiers feed into the exciting element of a light valve of a type, well known in the art, such as a recording galvanometer or a Kerr cell.

At a predetermined point in each recording amplifier, certain of the translated electrical energy is tapped off and is fed into an averaging device.

10 The averaging device has a balanced structure and is responsive to the difference in the magnitude of the energy fed to it from the individual amplifiers. The output of the balanced averaging device feeds into an exciting coil that regulates the position of a galvanometer mirror, and the mirror is thereby deflected in a direction corresponding to the predominating amplifier. The magnitude of the deflection corresponds to the average energy impinging on the sensitive element of the microphone corresponding to the predominating amplifier.

15 The recording light beam is modified by the light valve and is deflected by the mirror in a manner predetermined by the condition of the sound-translating devices and their corresponding amplifiers. A rectangle is thus imaged on a film-strip that has a width large in comparison with the long dimension of the rectangle, and the lateral position on the film at which the rectangle 20 is imaged corresponds to the position of the most highly excited microphone. That is to say, the position of the sound track on the film corresponds to the position of the object from which the sound of maximum intensity is being emitted.

25 30 35 When the film thus energized is printed and developed, a record is produced wherein the sound track has a lateral variation in position which corresponds to the variation in position of the bodies in the recording setting that originally emitted the sound.

40 45 The record is reproduced in a manner well known in the art. That is to say, an attenuated light beam is projected on the film and is modified in accordance with the character and disposition of the sound track. After being modified, the light impinges on the photo-sensitive elements of an elongated photo-sensitive device particularly adapted for the present purpose.

50 55 The photo-sensitive device preferably comprises a plurality of photo-sensitive electrodes and a plurality of collecting electrodes associated therewith. The collecting elements are disposed adjacent to the photo-sensitive elements and the electrodes are connected in independent circuits in such manner that energy is transmitted to the circuits in accordance with the localization of the light beam exciting the element.

60 65 70 The circuits into which the photo-sensitive electrodes feed are connected to independent amplifiers which, in turn, feed into independent loud speakers disposed adjacent to picture-producing screen in a manner corresponding to the original disposition of the microphones adjacent to the photographing stage. The amplitude of the sound produced in the loud speakers corresponds to the lateral disposition of the sound track on the film and, therefore, corresponds to the original disposition of the objects emitting the sound.

75 80 85 90 The novel features that I consider characteristic of my invention are set forth with particularity in the appended claims. The invention itself, however, both as to its organization and its method of operation, together with additional objects and advantages thereof will best be un-

derstood from the following description of a specific embodiment, when read in connection with the accompanying drawings, in which:

95 Figure 1 is a schematic drawing showing a recording system constructed according to my invention;

100 Fig. 2 is a diagrammatic view showing the essential elements of the averaging device in its relation to a record amplifier and the recording galvanometer;

105 Fig. 3 is a schematic view showing a reproducing system provided according to my invention;

110 Fig. 4 is a schematic view showing a photo-sensitive device particularly adapted to be utilized with apparatus constructed in accordance with my invention and the input elements for the amplifiers cooperating therewith; and

115 120 Figs. 5, 6, 7 and 8 are modifications of photo-sensitive devices that may be utilized in the practice of my invention.

125 The apparatus shown in Figs. 1 and 2 comprises a stage 1 having a plurality of microphones 3 and 5 disposed adjacent thereto. The microphones 3 and 5 feed into a plurality of independent amplifiers 7 and 9, and the output terminals 11 and 13 of the amplifiers are connected in parallel to a coil 15 whereby the position of the movable element 17 of a galvanometer 19 is predetermined.

130 135 140 The position of the movable element 17 of the galvanometer 19 is microscopically responsive to the energy transmitted to the exciting coil 15 from the amplifiers 7 and 9. By reason of its instantaneous variations in position, a light beam from a suitable source 21, which is suitably modified by an optical system 23, is deflected to produce an impression of variable width on a film strip 25 on which it impinges.

145 150 155 The above described recording process is well known in the art. However, according to my invention, the line of zero current-modulation of the sound track 27 on the film 25 is shifted in accordance with the position of the object from which the sound to be recorded is emanating.

160 165 170 175 The energy delivered by a predetermined element of the amplifiers 7 and 9 is fed into an averaging device 29. The averaging device has an output responsive to the influence of one of the amplifiers 7 and 9 in which the translated electrical energy predominates and feeds into the exciting coil 31 of a second galvanometer 33. The 180 movable element 35 of a galvanometer 33 is deflected and, in turn, deflects the beam of light which is reflected thereto from the mirror 17 of the microscopically-responsive galvanometer 19.

185 190 195 200 The moving element 35 of the galvanometer 33 is responsive to the microscopic condition of the sound emitted from a predetermined region of the stage 1 and deflects the line of zero modulation of the recording light beam in such manner that the lateral position of the region of the film strip 25 on which the sound track 27 is reproduced is a function of the disposition of the elements actually emitting the sound.

205 210 215 220 Although the system of recording illustrated herein is of the variable-area type, a record of the variable-density type may be produced in accordance with my invention in a manner which is apparent. In such a case, an optical valve, such as a Kerr cell, for example, is disposed between the film 25 and the microscopically responsive reflector 35, and the light beam is transmitted through it in a direction corresponding to the disposition of the sound-emitting elements on the recording stage.

225 230 235 240 It is, moreover, apparent that, if desirable, a

light valve of the glow-lamp type may be utilized, in which case, the source is so disposed relative to the microscopically-responsive mirror 35 that the light therefrom is suitably deflected before it impinges on the film.

Finally, it should be noted that, while, in the illustrated embodiment of my invention, two galvanometers are utilized, my invention may equally as well be practised with a single galvanometer that is biased in response to the directional effect of the sound and that responds to the instantaneous variations introduced by reason of the character of the sound in its biased positions.

15 In Fig. 2, a portion of one of the amplifiers 7 and 9, together with the averaging device 29, is shown in detail.

Each of the microphones 3 and 5 is connected in the grid circuit of an amplifier tube 37, in the plate circuit of which the primary windings 39 and 41 of a plurality of transformers 43 and 45 are connected. The secondary winding 47 of one transformer 43 is connected to the input of the next stage of amplification of the system, while 20 the secondary 49 of the other transformer 45 is connected to the terminals of a ballast lamp 51 that comprises one arm of a balanced circuit, such as a Wheatstone bridge. A balanced lamp 53, fed, in a similar manner, from the first stage 25 of amplification of the other amplifier 9, is connected in a conjugate arm of the bridge and the coil 31, whereby the mirror 35, responsive to the microscopic condition of the sound, is actuated, being connected between two conjugate terminals 30 55 and 57 of the bridge.

The bridge is adjusted by a plurality of variable resistors 59 and 61 in such manner that zero current is transmitted through the exciting coil 31 of the microscopic galvanometer 33 when the 40 sound energy impinging on one of the microphones 3 and 5 is substantially equal to that on the other. As the sound impinging on the microphones varies, the resistance of the ballast lamps 51 and 53, corresponding to the microphones, varies, and, if 45 the system becomes unbalanced, current is transmitted to the coil 31 of the galvanometer 33. The reflector 35 associated therewith is then deflected in such manner that the recording light beam impinges on the film 25 in a region corresponding to the relative magnitude of the predominating sound emitted and to the disposition 50 of the sound emitters.

It will be apparent to those skilled in the art that the ballast lamps 51 and 53 may be replaced by resistors of other types that respond with facility to variations in current transmitted through them. For example, grid-controlled thermionic tubes may be utilized in lieu of the lamps 51 and 53. In such case, the plate circuits of 55 the tubes constitute the arms of the bridge, while the grid currents of the tubes are fed from the amplifiers 7 and 9.

In Fig. 3, a reproducing system is shown schematically. The system comprises a light source 60 63, a condensing lens 67, whereby the radiations from the source 63 are gathered and focused on a slot 69, and a lens system 71 whereby the slot 69 is imaged on the film 25 in the form of an attenuated rectangle 73 extending across the 65 film 25.

A photo-sensitive device 75, comprising an elongated container 77 having disposed therein, a plurality of independent cathodes 79 and anodes 81, is located behind the film 25. The light transmitted through the film 25 and modified by the

sound track 27 impressed thereon impinges on the cathodes 79 of the photo-sensitive device 77. The cathodes 79 are energized in accordance with their disposition in the photo-sensitive device, and their state of excitation is dependent on the lateral orientation of the sound track on the film.

The current produced between each cathode 79 and its corresponding anode 81 is fed into a plurality of independent amplifiers 83, 85 and 87, which, in turn, feed into a plurality of loud speakers 89, 91 and 93. The loud speakers 89, 91 and 93 are arranged in the vicinity of the picture screen (not shown) in a manner corresponding to the microphones 3 and 5 in the recording setting, and it is seen that the magnitude of the sound reproduced by the loud speakers will be dependent on the state of excitation of the individual cathodes 79 and, therefore, on the original disposition of the sound-emitting bodies in the recording setting.

It is well to keep in mind that the loud speakers may be disposed behind the screen or adjacent to the screen, in a manner dictated by experience in installation. Moreover, the amplifiers 83, 85 and 87 and the speakers 89, 91 and 93 need not be of the same character. In certain reproducing equipment, I have found that the central amplifier 85 and its corresponding speaker 91 should preferably be capable of delivering more volume per unit input than the other reproducing members. By reason of such an arrangement, the amplification applied to the amplifiers transmitted to the terminal speakers 89 and 93 may be so limited that they do not become overloaded even if the original sound on one side of the stage 35 1 is comparatively loud.

In Fig. 4, a photo-sensitive device 95 of a type having a common cathode 97, a plurality of principal anodes 99 and a plurality of auxiliary anodes 101 is shown. The cathode 97 and the principal anodes 99 are respectively connected to the terminals of a plurality of inductors 103 which are the input elements to a plurality of amplifiers.

It is apparent that the anode associated with the region of the cathode wherein the radiant energy is localized will receive a greater charge than the anodes associated with the other regions of the cathode. Moreover, it is a well known fact that photo-electrons are emitted from the surface, in general, in a direction perpendicular to the surface. Consequently, if the cathode surface comprises a plurality of cylindrical arcs 105 and the anodes 99 are disposed at the centers of curvature of the arcs, the result produced by radiant energy of a localized character will correspond 50 with comparative accuracy to the localization of the energy.

The auxiliary anodes 101 are disposed between the principal anodes 99. The anodes 101 are connected to the mid taps 107 of the resistors 60 109 which, in turn, are connected to the lower terminals of the inductors 103. The auxiliary anodes 101 aid in smoothing out the characteristic response of the system and eliminate any abrupt effects that may arise by reason of the sudden transfer of the reproduction from one loud speaker to another. The photo-cell 95 of the type illustrated in Fig. 4 is particularly adapted to be utilized in apparatus of a type wherein the loud speakers in the central region of the reproducing stage are capable of delivering more power output than the speakers in the terminal regions of the stage.

In Fig. 5, a photo-sensitive device 107 having a plurality of individual cathodes 109 and a plu-

rality of principal and auxiliary anodes 111 and 113 associated with each cathode is shown. The purpose of the auxiliary anodes 113 in the photo-sensitive device 107 of the type illustrated in Fig. 5 is the same as the purpose of the corresponding anodes 101 in the device 95 of the type illustrated in Fig. 4.

In Fig. 6, a photo-sensitive device 115, comprising a single cathode 117 having plural-arc configuration and a single anode 119 associated with each arc, is shown.

In Fig. 7, a photo-sensitive device 121, of a type having a plane cathode 123 and a plurality of associated anodes 125, is illustrated.

In Fig. 8, a photo-sensitive device 127, incorporating a cathode 129 of the type having the configuration of an arc made up of a plurality of reentrant smaller arcs 131 is shown. A plurality of anodes 133 are associated with the smaller arcs 131.

With the exception of the photo-sensitive devices that may be utilized with my improved reproducing system, a single embodiment of my invention has been illustrated herein. The system has been shown, in general, schematically, and the improvements that are ordinarily incorporated in photo-acoustic and recording, reproducing systems are not shown. It is understood, however, that apparatus incorporating these improvements are equivalents which lie within the scope of my invention. In particular, it is set forth that a record constructed according to my invention may incorporate the ground-noise-reducing features which are beginning to be utilized in the motion-picture art. Again, it should be noted that, while modifications of photo-cells having independent anodes and a common cathode are illustrated and described hereinabove, my invention may be equally as well practiced with photo-cells having a common anode and a plurality of independent cathodes.

Finally, it should also be added that a sound record utilized in the practice of my invention should preferably be of the negative type. That is to say, the record should be of the type wherein the sound track region is transparent while the remaining region is opaque. By utilizing such a record, difficulties from ground noise are eliminated. For purposes of clarity, a positive record is shown in Fig. 3.

Although I have shown and described certain specific embodiments of my invention, I am fully aware that many modifications thereof are possible. My invention, therefore, is not to be restricted except insofar as is necessitated by the prior art and by the spirit of the appended claims.

I claim as my invention:

1. Directional photographic acoustic-recording apparatus comprising a plurality of devices for translating acoustic energy into electrical energy, said devices to be distributed in the region where the sound is to be produced, means for averaging the electrical energy produced in each translating device to displace the beam in accordance with the source of sound, a medium for receiving impressions of said translated electrical energy and means for localizing said impressions on said medium in accordance with the magnitude of the average energy produced from each of said translating devices.

2. Directional acoustic-recording apparatus comprising a plurality of devices for translating acoustic energy into electrical energy, said devices to be distributed in the region where the sound is to be reproduced in such manner that

the magnitude of the electrical energy delivered by each of said translating devices for a given sound is dependent on the relative position of the emitter of said sound, a medium for receiving impressions of said translated electrical energy, means to apply said impressions on said medium and means for varying the location of said impressions on said medium in accordance with the energy produced from each translating device.

3. In recording apparatus, means for translating acoustic energy into electrical energy one property of said means being responsive to the disposition of the source of said acoustic energy, and means for producing a permanent physical impression of said electrical energy, the last said means varying the location of said physical impression responsive to the directional effect produced in said translating means.

4. In apparatus for recording sound, means for producing an attenuated beam of radiant energy, said beam being responsive to the instantaneous condition of the sound to be recorded, and means for laterally displacing said beam in accordance with the relative position of the source of said sound, the magnitude of said lateral displacement being dependent on the distance of said source from a predetermined point.

5. In a system for recording sound in combination a balanced network having in each of a plurality of arms thereof a device capable of responding to the average value of the electrical energy supplied thereto, the output of said network being responsive to the relative conditions of said energy-responsive devices in each of the arms thereof, means for independently supplying electrical energy to each of said energy-responsive devices, means for projecting a light beam and means, to be actuated by the output of said network, for deflecting said light beam in accordance with the relative condition of each of said energy-responsive devices.

6. In combination a plurality of devices for converting acoustic energy into electrical energy, a balanced network having, in each of a plurality of arms thereof, a device capable of responding to the average magnitude of the electrical energy supplied thereto, the output of said network being responsive to the relative conditions of said energy-responsive devices in each of the arms thereof, means for coupling one of said energy-converting devices to each of said energy-responsive devices, means for projecting a beam of radiant energy and means, to be actuated by the output of said network, for deflecting said beam of radiant energy in accordance with the relative conditions of said energy-responsive devices.

7. In combination a film strip carrying a sound record, said record having a width small in comparison with said film strip and being laterally displaced on said film strip, the magnitude of said lateral displacement being varied in a predetermined manner, means for converting said record into electrical energy variations, a plurality of devices for translating electrical energy into acoustic variations and means for supplying said electrical energy variations to said energy translating devices in such manner that the magnitude of the output acoustic energy of any of said translating devices relative to that of the others varies in accordance with the variation of the lateral position of said record on said film strip.

8. In combination a film strip carrying a sound record, said record being laterally displaced on

5 said film strip and the magnitude of said lateral displacement being varied in a predetermined manner, means for converting said record on said film strip into electrical energy variations, a plurality of devices for translating electrical energy into acoustic energy and means for supplying said electrical energy variations to said energy translating devices in such manner that the output acoustic energy of any of said translating devices 10 relative to that of the others varies in accordance with the variation of the lateral position of said record on said film strip.

10. Apparatus for reproducing sound comprising a plurality of devices for translating electrical energy into acoustic energy, a medium having permanently impressed thereon a single record carrying the combined impression of the sound to be reproduced and of a predetermined space distribution of said sound in the region of 15 reproduction and means, to be energized in accordance with the impressions of said record on said medium, for supplying electrical energy to said translating devices whereby a sound is produced having a quality and a distribution corresponding to said record.

25 10. In combination a film strip carrying a sound record, said record being laterally displaced on said film strip and the magnitude of said lateral displacement being varied in a predetermined manner, means for converting said record on said film strip into electrical energy variations, said means including a photo-sensitive device having a single cathode and a plurality of anodes to cooperate with said cathode and optical means 30 for so projecting the impression on said film strip on said photo-sensitive device that the current in said device flows between said cathode and one of said anodes selected in accordance with the lateral position of said impression on said film strip, a plurality of devices for translating electrical energy into acoustic energy and means 35 for supplying said electrical energy variations to

said energy-translating devices in such manner that the response of said translating devices varies in accordance with the variation of the lateral position of said impression on said film strip.

11. In combination a film strip carrying a continuous sound record, said record being laterally displaced on said film strip and the magnitude of said lateral displacement being varied in a predetermined manner, means for converting the record on said film strip into electrical energy 10 variations, said means including a photo-sensitive device incorporating a plurality of pairs of elements, each element comprising a cathode and anode, in a single container, and optical means for so projecting the record on said film strip on 15 said photo-sensitive device that the current in said device at any time flows between one of said pairs of elements selected in accordance with the lateral position of said impression on said film strip, a plurality of devices for translating electrical energy into acoustic energy and means 20 for supplying said electrical energy variations to said energy translating devices in such manner that the output acoustic energy of any of said translating devices varies relative to that of the 25 others in accordance with the variation of the lateral position of said record on said film strip.

12. Apparatus for reproducing sound comprising a plurality of devices for translating electrical energy into acoustic energy, a photo-sensitive 30 device that is capable of selectively responding in accordance with the localized effect of radiant energy impinging thereon, a medium having impressed thereon a single record of sound, said record being localized in said medium in a manner 35 corresponding to a predetermined distribution of said sound in the reproducing medium, means for energizing said photo-sensitive device in accordance with said record and means for energizing said translating devices in accordance 40 with the output of said photo-sensitive device.

WM. MAURICE PATTERSON.
